PIPE STEM AND THE LIKE

Roy F. Darnell, Detroit, Mich., assignor of one-half to John S. Wilson, Detroit, Mich.

Application September 12, 1932, Serial No. 632,846

8 Claims. (Cl. 131—12)

This invention relates to improvements in pipe stems and the like and has as its principal object to simplify, render more efficient, and improve generally structures of this type.

5 The invention has as one of its primary objects to provide, in a pipe stem, cigarette holder or the like, means for preventing saliva or other moisture from entering the stem from the open or tip end thereof.

10 Another object of the invention is to provide a construction of this character which may be quickly and economically manufactured and easily assembled with the stem.

15 Another object of the invention is to provide a construction of this type in which neither the valve nor its operation thereof will interfere with the normal or natural use or enjoyment of the pipe, cigarette holder or the like.

Another object of the invention is to provide 20 a construction of this character in which the principal operating parts of the valve structure are encased or enclosed in a housing and protected from contact with the nicotine laden smoke which passes through the stem.

25 Still another object of the invention is to provide a pipe stem constructed in this manner but which may be readily cleaned by the conventional type of pipe cleaners by readily passing the same longitudinally therethrough.

30 Other objects, advantages and novel details of construction of this invention will be made more apparent as this description proceeds, especially when considered in connection with the accompanying drawing wherein

35 Fig. 1 is a longitudinal sectional view through a pipe having a stem constructed in accordance with this invention;

Fig. 2 is a fragmentary sectional view through the stem of the pipe taken at right angles to 40 Fig. 1;

Fig. 3 is an enlarged detail sectional view taken substantially on the plane indicated by line 3—3 in Fig. 1;

45 Fig. 4 is a similar view taken substantially on the plane indicated by line 4—4 in Fig. 1, and

Fig. 5 is an end elevational view of the tip end of the stem.

50 Referring now more particularly to the drawing wherein like reference characters indicate like parts, it will be noted that there is illustrated a pipe comprising a bowl 10 having an integral tubular stem portion 11 projecting therefrom and the usual removable stem 12 secured in any desired or preferred manner to the integral stem section 11.

The integral stem section 11 is provided with a passage 13 which communicates with the bowl of the pipe and in the present illustrative embodiment of the invention this passage 13 is illustrated as terminating in a pair of branch passages 14 which communicate with the passages yet to be referred to in the removal stem section 12.

5 The stem 12 is provided longitudinally and centrally thereof with a pair of opposed substantially semi-circular grooves or recesses 15 arranged in opposed relation and adapted to receive and accommodate a substantially tubular housing 16 formed preferably of the same material as the stem section 12. This housing member 16 is introduced into the stem 12 from the end thereof opposite the bit end 17 before the stem section 12 is secured to the integral stem section 11. Movement of the housing member 16 toward the tip end is arrested or limited by the engagement of shoulders 18 on the housing with shoulders 19 formed in the grooves 15.

10 The location of the housing 16 in the stem 12 divides the longitudinal passage thereof into a pair of passages 20 which provide communication between the open bit end 17 of the stem and the branch passages 14 heretofore referred to.

15 Arranged longitudinally within the housing 16 is a rod or stem member 21 which is provided at one end thereof with a valve member 22 shaped to correspond to the opening 23 in the tip end of the stem and adapted to close this opening by engaging an annular valve seat 24 surrounding the opening 23.

20 Surrounding the rod 21 is a light coil spring 25 which bears on the one end against a shoulder 26 formed within the housing and on the other end against a washer or the like 27. The washer 27 is held on the rod 21 by providing an abutment 28 on the rod, as for instance by flattening 25 the same as illustrated. The housing 16 throughout a portion of its length, as for instance at 29, may be provided with a bore of a diameter such as will slidably receive the rod 21 whereby this rod is guided in its longitudinal movement. The 30 other end of the housing 16 is preferably closed by means of a movable plug or the like 30.

25 As will be observed, the valve member 22 normally closes the opening 23 in the bit end of the stem 12. However, when the pipe user draws on the pipe the suction thus created acts to open the valve 23 against the action of the light spring 25 to thus permit smoke to be drawn out through the stem from the bowl of the pipe. However, whenever the pipe user ceases to draw on the 35

pipe the spring 25 acts to immediately seat the valve 22 on the seat 24 to thus prevent the entrance of saliva or other moisture from the mouth of the smoker into the pipe stem. This prevents 5 the accumulation of moist tobacco, nicotine, and saliva in the stem and also in the base of the pipe bowl, and thus insures a clean, moistureless and fragrant smoke.

Only a slight suction is required to unseat the 10 valve 22 so that the use of a pipe having a stem constructed in accordance with this invention will not in any manner whatsoever interfere with the normal use and enjoyment of the pipe. Moreover, the tapered or inclined contour of the valve 15 seat 24 and of the engaging portion of the valve insures an adequate seating of the valve under all normal conditions.

As will be noted, the rod 21 throughout the 20 greater portion of its length, together with the spring 25 and the abutment 27, are all enclosed within the housing 16 so as to be kept out of contact with the nicotine laden smoke which passes 25 through the stem so that the smoke is not contaminated thereby and these parts are kept free from nicotine deposits which might cause 30 corrosion or rust and interfere with their normal operation.

The pipe may be readily cleaned in the usual 35 conventional manner by drawing the valve member 22 outwardly against the action of the spring 25 and rotating the same a quarter turn so as to position the valve 22 crosswise of the oval-shaped opening 23. This position of the valve 22 is illustrated in dotted lines in Fig. 5 and, as will be observed, leaves the opening 23 in the tip of the 40 stem open on opposite sides of the valve whereby the conventional type of pipe cleaner may be inserted into the stem through the passages 20 and then through the branch passages 14 and the passage 13 to the bowl of the pipe, if desired. If the stem section 12 is removed from the pipe, the pipe cleaner may be run completely through the 45 stem as will be obvious.

To those skilled in this art, it will be immediately 45 apparent that the principles of this invention may be applied with equal facility and with the same advantageous results to the stem of a cigarette holder or any similar type of smoking implement, and to this end the invention contemplates all types of smoking implements employing stems.

Reservation is made to make such changes as may come within the purview of the accompanying claims.

55 What I claim as my invention is:

1. The combination with the stem of a smoking implement, of a check valve for controlling the passage through said stem, and a housing located within said passage providing means for mounting said valve and enclosing the control means therefor to protect the same from contact with the smoke passing through the stem passage.

2. In a structure of the class described, a stem having a smoke passage therethrough, a check valve for controlling said smoke passage, a housing for mounting said check valve and providing

a protective enclosure for the control means therefor, and means for mounting said housing within the passage of said stem.

3. In a smoking implement, a stem provided with a smoke passage therethrough, a check valve located in the bit end for controlling said smoke passage, a removable housing located in said passage of said stem and providing mounting means for said valve, and spring means enclosed in said housing for holding said valve in closed position, 10 said housing forming a protective enclosure for said spring means whereby the smoke and atmosphere cannot reach the spring.

4. In a smoking implement, a stem provided with a smoke passage therethrough, a housing, means in said smoke passage for mounting said housing, a valve rod slidably mounted in said housing, a valve carried by said rod and acting to control said passage, and spring means enclosed 15 in said housing for holding said valve in closed 20 position.

5. In a smoking implement, a stem provided with a passage therethrough, a valve seat surrounding said passage at the bit end of said stem, an outwardly opening valve engaging said seat, a housing member located in said passage, a rod connected to said valve and slidably mounted in said housing member, and a spring surrounding 25 said rod in said housing and engaging a stop on the end of said rod to normally hold said valve in 30 engagement with said valve seat, for the purpose set forth.

6. In a smoking implement, a stem provided with a passage therethrough, a pair of opposed 35 grooves formed in the wall of said passage, a housing member fitted in said grooves, a check valve at one end of said stem, a valve rod connected thereto and extending into said housing, and a spring in said housing engaging said rod to normally hold said valve in closed position, for the 40 purpose set forth.

7. In a smoking implement, a stem provided with a passage therethrough and a valve seat at one end thereof, an outwardly opening check valve 45 normally engaging said seat, a pair of opposed grooves formed in the wall of said passage with a shoulder intermediate the ends thereof, a housing fitted into said opposed grooves and provided with a shoulder engaging the shoulder aforesaid to limit movement of said housing toward said 50 valve, a rod connected to said valve and extending into said housing, means for slidably mounting said rod in said housing, and spring means within said housing engaging said rod for normally holding said valve in engagement with its seat.

8. In a smoking implement, a stem having a smoke passage therethrough and a valve seat at one end thereof, a valve normally engaging said seat, a valve rod connected to said valve and extending into said passage, a housing fixed within 60 said smoke passage, said housing having means for slidably and rotatably mounting said valve rod, and spring means within said housing normally holding said valve in engagement with its seat.

65 ROY F. DARNELL.
